US0D1065044S

(12) **United States Design Patent** (10) **Patent No.:** **US D1,065,044 S**
(45) **Date of Patent:** **** Mar. 4, 2025**

(54) **SOLAR COLLECTOR**

(71) Applicant: **YOUNGJIN ENERGY INTERNATIONAL Co., Ltd.**
Uiwang-si (KR)

(72) Inventor: **Sung Bok Shin**, Seoul (KR)

(73) Assignee: **YOUNGJIN ENERGY INTERNATIONAL Co., Ltd.**
Uiwang-si (KR)

(**) Term: **15 Years**

(21) Appl. No.: **29/887,783**

(22) Filed: **Mar. 24, 2023**

(30) **Foreign Application Priority Data**

Mar. 13, 2023 (KR) 30-2023-0009237

(51) **LOC (15) Cl.** **13-04**

Yongsok Choi, Esq.

(57) **CLAIM**

The ornamental design of a solar collector, as shown and described.

DESCRIPTION

FIG. 1 is a perspective view of a solar collector showing the claimed design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets
